ADHESIVE TAPE SALES TICKET

Ralph E. Johnson, Indianapolis, Ind.

Application October 31, 1941, Serial No. 417,307

3 Claims. (Cl. 40—2)

This invention relates to a combined sales ticket and package sealing tape having use in stores where packages are wrapped and secured by means of a length of adhesive tape and a sales ticket accompanies the package for presentation to a cashier or the like.

The invention has for a primary object the combination of a sales ticket with adhesive tape whereby, for example, in a butcher shop within a grocery store, the meat cutter may wrap up a quantity of meat with a paper wrapper and pull the tape through the usual moistening device, tear off a suitable length and apply it over the end of the paper wrapper to seal the package, and at the same time have that length of tape carry preferably two sales tickets on which the meat cutter may indicate his assignment number and the price of the meat within the package. The package thus sealed and having the sales tickets applied thereto is carried by the customer to the checker who tears off the two sales tickets, placing the tickets on file for later use, one ticket to the bookkeeper or auditor, and the other duplicate ticket back to the meat cutter for his checking of business in his own department. The sales tickets referred to are united to the tape and folded thereover to be removed from the adhesive side. Preferably the tickets are attached to the tape along perforated lines.

The advantage of the invention is readily apparent in that the meat cutter is able to save a considerable amount of time as compared with the heretofore employed method of having a pad of separate tickets independent of the tape, wherein the meat cutter was obliged first to pull a length of tape out from the dispensing machine and apply it to the package, lay down the package, take the pad of tickets out of his pocket or lift it up from the counter, fill in the tickets, and then attach them to the package. In other words, over a period of time, the meat cutter is able to give attention to more customers.

These and other objects and advantages of the invention will become apparent to those versed in the art in the following description of one particular form of the invention as illustrated in the accompanying drawing, in which

Fig. 1 is a view in perspective of a roll of tape embodying the invention; and

Fig. 2, a view in plan of a length of the tape in unfolded condition.

Like characters of reference indicate like parts in the two views in the drawing.

Paper of the desired quality, weight and tex- 55 and the structure employed is exceedingly simple

ture, is formed in a strip and perforated along a line 10 longitudinally thereof, preferably along the center line. The area of the strip to one side of the line 10 is transversely divided by perforated lines 11, these lines 11 defining therebetween a price or sales ticket 12.

On the other side of the line 10, the entire area is coated with a suitable adhesive 13 of that character which will permit the strip to be rolled with the adhesive against a non-adhesive coated face of the strip to permit the unwinding of the strip from a roll. The composition of this adhesive does not enter into the invention per se but may be of any of the usual and well known types, such as the adhesive commonly employed on sealing tapes requiring moisture, or the rubber or latex type requiring no moisture.

The strip above defined is folded along the line 10 to carry the tickets 12 around against the uncoated side of the strip whereby the strip may be rolled into that form shown in Fig. 1 to have the adhesive side undermost and the ticket side uppermost when the end of the strip is pulled out from the roll. Such a roll may be employed in the usually tape dispensing machine (not shown) whereby the end is pulled out over a moistening roller and a cut off device. In any event the end of the tape is pulled out from the roll and applied to the desired package with the adhesive face against the package to leave the sales tickets secured to that length of tape employed and presented on the top side of the tape.

The length of tape may be cut off in the suggested dispensing machine at the end of the second ticket 12, or the part of the tape which is coated with adhesive 13 may be transversely perforated from the line 10 along lines 14 continuing across from every second line 11, so that the tape may be easily severed along the correct line to leave the two tickets 12 available. Of course the invention is not limited to the precise number of tickets 12 since the number employed will vary with the system in operation in the particular store that may employ the invention. It may be desirable to use only one ticket 12 or even three or four on the same package and this would be determined by the length of tape used on the package and the number of perforated lines 11 provided.

It is therefore to be seen that by so forming the tape as above indicated, the under side of the tape serves not only to seal the package but also to carry initially integrally therewith the desired sales ticket or tickets directly on the package, and the structure employed is exceedingly simple

in operation and relatively low in cost, all tending to a more economical and accurate system of the business.

While I have herein shown and described my invention in the one particular form, it is obvious that structural variations may be employed without departing from the spirit of the invention and I therefore do not desire to be limited to that precise form beyond the limitations as may be imposed by the following claims.

I claim:

1. Sealing packages and ticket holding means comprising a tape folded along a longitudinally extending line to have an under portion, the underside of which is coated with an adhesive, and to have an upper portion extending from said line in overlapping relation with said under portion, said upper portion having transverse severing lines defining tickets therebetween along said fold line, said fold line being perforated whereby the said ticket portions may be readily removed from the adhesive coated portion when that portion is applied to and secured on a package.

2. Sealing package and ticket holding means comprising a tape folded along a longitudinally extending line to have an under portion, the underside of which is coated with an adhesive, and to have an upper portion extending from said

line in overlapping relation with said under portion, said upper portion having transverse severing lines defining tickets therebetween along said fold line, said fold line being perforated whereby the said ticket portions may be readily removed from the adhesive coated portion when that portion is applied to and secured on a package, and severing lines extending laterally across said adhesive coated tape portion and in continuation with some at least of said ticket severing lines.

5 3. Sealing package and ticket holding means comprising a tape folded along a horizontally extending line to have an under portion, the underside of which is coated with an adhesive, and to have an upper portion extending from said line in overlapping relation with said under portion, said upper portion having transverse severing lines defining tickets therebetween along said fold line, said fold line being perforated whereby the said ticket portions may be readily removed from the adhesive coated portion when that portion is applied to and secured on a package, said ticket severing lines consisting of rows of perforations spaced to permit ready tearing of the tape therebetween, and a line of perforation extending transversely across said adhesive coated portion in continuation of every second said ticket line.

20 25 RALPH E. JOHNSON.
